UNITED STATES PATENT OFFICE.

CHARLES H. ELDON, OF WILLIAMSPORT, PENNSYLVANIA.

DESIGN FOR A HANDLE-BAR GRIP FOR BICYCLES.

SPECIFICATION forming part of Design No. 28,992, dated July 5, 1898.

Application filed August 27, 1897. Serial No. 649,784. Term of patent 14 years.

To all whom it may concern:

Be it known that I, CHARLES H. ELDON, a citizen of the United States, residing at Williamsport, in the county of Lycoming and State of Pennsylvania, have invented a new and original Design for a Handle-Bar Grip for Bicycles, of which the following is a specification.

This invention relates to a new and original design for a handle-bar grip for bicycles; and it has for its object to provide a design of this character that shall be both useful and ornamental.

The leading feature of the design resides in a cylindrical body provided therein with annular rows of perforations or holes and exterior circumferential ribs or beads arranged between the rows of perforations or holes.

A minor feature of the design resides in the cylindrical body having at its ends circular knobs and a regular series of interior scallops encircling the inner portions of said knobs.

In the drawings, Figure 1 is a perspective view of a handle-bar grip for bicycles embodying the herein-described design. Fig. 2 is a longitudinal sectional view thereof. Fig. 3 is a cross-sectional view on the line 3-3 of Fig. 2.

Referring to the accompanying drawings, the numeral 1 designates the hollow cylindrical body of the grip, which is illustrated as being provided with plain circular end portions 2, beyond which are extended circular end knobs 3. The said hollow cylindrical body 1 of the grip is provided within the plain circular end portions 2 thereof with a circular series of interior scallops 4, which encircle the inner portions of the knobs 3. Between the plain interiorly-scalloped end portions 2 the body 1 is provided with a series of annular rows of perforations or holes 5 and with a series of exterior continuous circumferential ribs or beads 6, projected beyond the plane of the perforations or holes and alternating with the separate rows thereof.

What I claim is—

The design for a handle-bar grip for bicycles herein shown and described.

In testimony that I claim the foregoing as my own I have hereto affixed my signature in the presence of two witnesses.

CHARLES H. ELDON.
